UNITED STATES PATENT OFFICE

162,782

MOTION-PICTURE CAMERA

Jacques Jean Georges Gaston Broido,
Carouge-Geneva, Switzerland

Application June 26, 1950, Serial No. 10,767
In Italy April 12, 1950

Term of patent 14 years

(Cl. D61—1)

To all whom it may concern:

Be it known that I, Jacques Jean Georges Gaston Broido, a citizen of Switzerland, residing at Carouge-Geneva (Switzerland) 7 Rondeau, have invented a new, original, and ornamental Design for a Motion Picture Camera, of which the following is a specification, reference being had to the accompanying drawing, forming part hereof.

The figure is a side perspective view of a camera, showing my new design, the opposite side being plain.

I claim:

The ornamental design for a motion picture camera, substantially as shown and described.

JACQUES JEAN GEORGES
GASTON BROIDO.
